THERMOLYTIC CONVERSION OF HYDRO-CARBON GASES TO LIQUID

John W. Throckmorton, New York, N. Y., assignor to The Pure Oil Company, Chicago, Ill., a corporation of Ohio

Application July 23, 1937, Serial No. 155,152

12 Claims. (Cl. 196—10)

This invention relates to method and apparatus for converting hydrocarbon gas to liquid hydrocarbons and is more particularly concerned with method and apparatus for efficiently converting hydrocarbon gas mixtures into gasoline type hydrocarbons.

In the operation of thermolytic gas polymerization processes it is difficult to obtain complete conversion of the reactable constituents in a one step system without the necessity of high recycle ratios. But high recycle ratios mean low throughput with resultant low output and high operating cost.

In accordance with this invention the charging gas is fractionated so as to separate the C₂ hydrocarbons and lighter gas from a fraction containing C₃ and heavier hydrocarbons. The latter fraction is charged through suitable heating and reaction zones separate from the light fraction, wherein it is subjected to suitable conditions of time, temperature and pressure to convert a substantial portion to gasoline boiling hydrocarbons.

The light fraction may or may not be further fractionated to remove the lightest constituents such as hydrogen and methane, and then charged to a separate cracking coil preferably operated at higher temperatures and lower pressures than the coil to which the heavy fraction is charged. In the cracking coil conversion of gas to liquids 30 and to olefins takes place. The desirable portions of the reacted gas are absorbed in a liquid-oil menstruum and the rich oil used to chill the reaction products from the high pressure coil. The combined products are then fractionated 35 and the resulting gas is mixed with the fresh charge. In this manner, the desirable portions of the gases from the reaction zone are recovered and mixed with the fresh gas after elimination of the fixed gas, low in polymerizable constituents, from the system, and a uniform blend of finished gasoline is obtained all in a single operation.

By using a two step operation of the type above described the recycle in the high pressure coil may be maintained between the limits of ½ to 2 parts of recycle gas to 1 part of fresh gas, with a much lower recycle ratio in the low pressure coil. Moreover, the use of the two step system enables the maintenance of optimum conditions for the products charged to each coil, resulting in longer runs without excessive coke formation. The throughput and gasoline yield are greatly augmented, and operating costs are correspondingly decreased because of lower over-head.

In order to more fully comprehend the nature and scope of the invention, reference should be had to the following description together with the accompanying drawing of which

The single figure is a diagrammatic elevational view of apparatus suitable for carrying out the invention.

Referring to the drawing, the numeral 1 indicates a line through which fresh gas is charged to the system by means of pump or compressor 3. The charging gas may be natural or cracked gas, gas from a liquid or vapor phase oil cracking operation, or other gas containing a substantial amount of C₃ and C₄ hydrocarbons. The charging gas is then pumped through line 5 and cooler 7 to gas and liquid separator 9. If the charge is gaseous it may be compressed in compressor 3 to a pressure of approximately 150-350 pounds per square inch and cooled to a temperature of 80°-100° F. before entering the gas separator. If the charge is liquid, the same conditions of temperature and pressure should be maintained.

The liquid fraction consisting chiefly of C₃ and C₄ hydrocarbons is withdrawn from the lower part of the gas separator through line 11 by means of pump 13, and may be charged through line 15 controlled by valve 17, to the inlet of coil 19 located in furnace 21 at a pressure ranging from 200-3000 or more pounds per square inch.

The pressure, under which the charge to the coil 19 is maintained, will depend largely upon the composition of the charge and upon the product desired. If the charge contains substantially only saturated hydrocarbons, pressures of approximately atmospheric to 250 pounds per square inch and temperatures of approximately 1200°-1300° F. will be preferably maintained with a short reaction period in order to convert the saturated hydrocarbons to unsaturates. In such case the products, after leaving the heating coil, may be chilled at 23 by means of a portion of the fresh charge which is by-passed through line 25 controlled by valve 27 to a temperature of approximately 1075°-1200° F. and then passed to 45 a reaction coil or chamber 29 maintained under substantially the same pressure as the cracking coil, wherein the products are given sufficient time to polymerize to hydrocarbons boiling within the gasoline range. The reaction coil 29 is preferably provided with means for controlling temperature. For this purpose the coil or chamber may be enclosed in a suitable vessel through which a draft of air, combustion gases, or other heat exchange or cooling means may be passed. 50

If the charge to the coil 19 contains approximately 20% or more of olefinic hydrocarbons, it 5 may be heated in the coil 19 to a temperature between approximately 800°-1050° F. under pressure of 500-3000 or more pounds per square inch, and these temperature and pressure conditions maintained in the reaction coil; or if it is desired to produce primarily aromatic hydrocarbons, the charge may be maintained under a 10 pressure of approximately atmospheric to 250 pounds per square inch and at temperatures of 1075°-1200° F.

The products issuing from the reaction coil 29 may be suddenly chilled to a temperature of 15 approximately 600° F. or lower by direct contact with an intermediate oil fraction formed in the system and which is injected into the issuing products at the point 31. Depending upon the 20 pressure maintained in the reaction coil, the pressure on the reaction products may or may not be reduced at the valve 33 and the products then passed into the lower portion of fractionating tower 35. The temperature of the reaction products, after chilling, should be high enough 25 to permit fractionation thereof without additional heating.

The reaction products are separated in the fractionating tower 35 into residual oil, an intermediate fraction boiling above the gasoline range, 30 which is collected on the plate 37, gasoline boiling hydrocarbons which are collected on the plates 39 and 41, and residual gas which comes over the top of the tower through line 43. The residuum is withdrawn from the bottom of the 35 fractionating tower through line 45 controlled by valve 47, at which the pressure is reduced to approximately atmospheric pressure, and the oil is flashed in flash tower 49 into vapors and tar. The residual tar is withdrawn from the flash 40 tower through line 51, by means of pump 53, through cooling coil 55, to any suitable place of storage. The vapors are withdrawn from the flash tower through line 57 and condenser 59 into separator 61. Any uncondensed material is 45 withdrawn from the separator 61, through line 63, and eliminated from the system. The condensate is recycled through line 65, by means of pump 67, to an intermediate portion of the fractionating tower 35, as reflux. This reflux preferably 50 enters the tower at a point intermediate the trays 37 and 39.

The gasoline boiling constituents are withdrawn from the fractionating tower through line 69 controlled by valve 71 and line 73 controlled 55 by valve 75 and pass through a common line 77 into a stripper 79. In the stripper light hydrocarbons, such as C₃ and a portion of the C₄ hydrocarbons, are vaporized and taken overhead through the line 81. The stripper 79 is preferably 60 provided with suitable fractionating plates and heating means in order to stabilize the gasoline. The stabilized gasoline may be withdrawn from the stripper through lines 83 and 85 and passed to storage through line 87 controlled by valve 89.

The pressure in the fractionating tower 35 is 65 preferably maintained at approximately 175-250 pounds per square inch and the temperature at the top of the tower is maintained sufficiently 70 low to condense the major portion of the gasoline fraction. The incondensable gases together with a small amount of uncondensed gasoline vapors leave the fractionating tower 35 through line 43, then pass through condenser 91, into gas and liquid separator 93. The condensate from sepa-

rator 93 is recycled through line 95 by means of pump 97, as reflux, to the upper portion of the fractionating tower 35. The gases which remain uncondensed are withdrawn from the upper portion of the separator 93, through line 99, and join the fresh gas in the line 5, to be reprocessed. 5

The gases which are not liquefied in the separator 9 are withdrawn from the top thereof through line 101 controlled by valve 103 and charged to the inlet of the cracking coil 105 located in the furnace 107. If desired, the gases withdrawn through the line 101 may be further fractionated by being by-passed through line 109, compressed by compressor 111, and charged to separator 113. In this manner the hydrogen and 15 methane may be eliminated from the gas prior to charging to the cracking coil. The gases will be compressed in compressor 111 sufficiently to liquefy the C₂ fractions in order to separate them from the hydrogen and methane which are eliminated from the system through line 115 controlled by valve 117. The liquefied C₂ fractions may be withdrawn from the separator 113, through line 119 controlled by valve 121, and charged to the inlet of the cracking coil 105. 20

When the gases charged to the cracking coil 105 are not further fractionated they are preferably charged thereto in the gaseous state under pressure of from 50-100 pounds per square inch. The gases may be heated in the cracking coil to 30 temperatures of 1200°-1600° F. The temperature and pressure conditions maintained in this coil 105 will be those most suitable for obtaining maximum yield of gasoline boiling hydrocarbons. If the fraction removed from separator 9 through 35 line 101 is low in olefinic hydrocarbons, high temperatures and low pressures, such as those above mentioned, are preferably maintained in the coil 105. If the olefinic content of these gases is sufficiently high, that is, above approximately 40 20%, it may be advantageous to further fractionate them to remove the hydrogen and methane, and charge the remaining gas in the liquid or gaseous phase to the coil 105. If liquid phase charging is employed, the pressures maintained 45 in the coil 105 may be 500-3000 or more pounds per square inch and the temperatures preferably between 700° and 1000° F. If the olefin content is sufficiently high to avoid necessitating further fractionation, the gases charged to the coil 105 50 may be maintained at low pressures of approximately atmospheric to 250 pounds per square inch and at temperatures of approximately 1100°-1200° F. It will be understood, however, that these conditions of temperature and pressure may be varied in accordance with the composition of the charge to the coil. The reaction time will vary with the pressure and temperature conditions maintained. Generally the reaction 55 time will vary directly with the pressure and inversely with the temperature.

In the coil 105 cracking and/or polymerization of the gases take place in the formation chiefly of liquid hydrocarbons and olefinic gases. The reaction products issue from the cracking coil 60 through the line 123 and are suddenly chilled by direct contact with an intermediate condensate formed in the process, which is introduced into the line 123 at the point 125. The partially chilled reaction products are further cooled by 65 passing through the cooling or condensing coil 127, and then pass through line 129 controlled by valve 131, into gas and liquid separator 133. From the separator 133 any liquid products are withdrawn through the line 135 by means of 70 75

pump 137. The gases are withdrawn by means of the compressor 189 through line 141 and cooling coil 143 and charged to the lower portion of the absorber 145.

Intermediate condensate substantially boiling within the range of gas oil is withdrawn from the fractionating tower 35 through line 147 by means of pump 149 and passes through cooling coil 151. From the cooling coil 151 a portion of the condensate passes through line 153 and valve 155 to the line 123 where it is injected into the reaction products from the coil 105 in order to cool these products below reaction temperature. The remaining portion of the condensate passes through line 157 controlled by valve 159 into the upper portion of absorber 145 wherein it passes counter-currently to the gases entering the bottom of the absorber. The pressure in the absorber may be preferably between 175-225 pounds per square inch and the temperature approximately 75°-100° F. Under these conditions of temperature and pressure substantially all the C₃ and heavier hydrocarbons will be absorbed as well as a substantial portion of the C₂ hydrocarbons, mainly ethylene. The hydrogen, methane and the main portion of the C₂ hydrocarbons are eliminated from the absorber and from the system through line 161 controlled by valve 163.

Rich oil leaves the bottom of the absorber through line 165 and is charged by pump 167 through line 169 into line 171. The liquid hydrocarbons from the separator 133 join the rich oil in the line 169. The stream of rich absorber oil together with the liquids from separator 133 may be split in the line 171, a portion passing through valve 173 and entering the line 30 at the point 31 in order to chill the reaction products below reaction temperature, and another portion passing through the valve 175 into the intermediate portion of the fractionating tower above the plate 37 to act as reflux.

In the fractionating tower the absorber oil is stripped of its gases which pass over from the tower through line 43 and are processed as heretofore described.

By virtue of the fact that substantially all the C₂ and lighter gases are eliminated from the charge to the coil 19, the recycle ratio to this coil is kept low allowing for a greater throughput of fresh charging stock. Moreover, the elimination of these light gases permits the maintenance of those conditions in the coil 19 and reaction coil 29 which will produce the maximum amount of desired product. The C₂ and lighter fractions, after having been subjected to a combined cracking-polymerization operation, or to polymerization alone, in the coil 105, are substantially eliminated from the system through the line 161, only a relatively small portion thereof being absorbed in the absorber and recycled to the system.

What is claimed is:

1. The process of converting gas mixtures, containing chiefly C₂, C₃ and C₄ hydrocarbons, to liquid hydrocarbons which comprises separating the mixture into a fraction containing chiefly C₃ and C₄ hydrocarbons and another fraction containing C₂ hydrocarbons and lighter gases, subjecting each fraction in a separate zone to suitable conditions of time, temperature and pressure for converting the gaseous constituents to liquid hydrocarbons boiling within the gasoline boiling range, separating the bulk of the C₂ and lighter gases from the reaction products of the

lighter gases and eliminating them from the system, charging the remainder of the reaction products resulting from said conversion of the lighter gases to a common fractionating zone together with the reaction products of the C₃, C₄ hydrocarbons, separating the incondensable gases from the normally liquid hydrocarbons, and uniting the incondensable gases with the fresh gas prior to separation thereof into fractions.

2. The process of converting gas mixtures, containing chiefly C₂, C₃ and C₄ hydrocarbons, to liquid hydrocarbons which comprises separating the mixture into a fraction containing chiefly C₃ and C₄ hydrocarbons and a fraction containing C₂ and lighter gases, subjecting each fraction in a separate zone to suitable conditions of time, temperature and pressure to convert a substantial portion of the gaseous constituents to liquid hydrocarbons boiling within the gasoline range, separating the resulting products from the lighter fraction conversion into liquids and gases, contacting the gases under pressure with absorber oil in order to absorb the major portion of the C₃ and C₄ hydrocarbons, charging rich absorber oil into a common fractionating zone with the reaction products of the C₃, C₄ fraction, separating normally gaseous hydrocarbons from the normally liquid hydrocarbons in said fractionating zone, and mixing the normally gaseous hydrocarbons with fresh gas prior to separation thereof into fractions.

3. Process in accordance with claim 2 in which the rich absorber oil is used to chill the reaction products of the C₃, C₄ fraction below conversion temperature, and the chilled mixture charged to the common fractionating zone.

4. Process in accordance with claim 2 in which the liquid reaction products from the conversion of the C₂ and lighter gases are charged to the common fractionating zone.

5. Process in accordance with claim 2 in which a condensate heavier than gasoline is withdrawn from the fractionating zone and cooled, and a portion of the cooled condensate used to chill the reaction products of the C₂ and lighter gases below reaction temperature and another portion used as the absorption menstruum.

6. Process in accordance with claim 2 in which the gas mixture charged to the process contains a substantial proportion of C₃ and C₄ olefins, and in which the C₃, C₄ fraction is subjected to conversion at temperatures of 800°-1050° F. and at pressures above 500 pounds per square inch while the C₂ and lighter gas fraction is subjected to conversion at temperatures between 1200° and 1600° F. and under pressures below 100 pounds per square inch.

7. Process in accordance with claim 2 in which the gas mixture charged to the process is rich in olefins and in which the fraction containing the lighter gases is further fractionated to remove methane and hydrogen, and the remainder of the fraction is subjected to temperatures between 700° and 1000° F. under pressures above 500 pounds per square inch while the C₃, C₄ fraction is subjected to temperatures of approximately 1075°-1200° F. under pressures up to approximately 250 pounds per square inch.

8. Process in accordance with claim 2 in which the gas mixture charged to the process is rich in olefins and in which the fraction containing the lighter gases is further fractionated to remove methane and hydrogen, and the remainder of the fraction is subjected to temperatures between 700° and 1000° F. under pressures above 75

500 pounds per square inch while the C₃, C₄ fraction is subjected to temperatures of approximately 800°-1050° F. under pressures above 500 pounds per square inch.

- 5 9. Apparatus for converting hydrocarbon gases to liquid hydrocarbons comprising means for separating gases into a light fraction and a heavy fraction, means for charging mixed gases to said separating means, a heating and reaction means, 10 means for charging said light fraction to said heating and reaction means, a second heating means and a second reaction means connected thereto, means for charging said heavy fraction to said second heating means, means for cooling the reaction products from said first heating and 15 reaction means, means for separating normally liquid from normally gaseous constituents in said cooled products, means for contacting said gaseous constituents with absorber oil under such 20 conditions as to absorb substantially only the heavier portions of said gaseous constituents, means for eliminating the unabsorbed constituents from the system, means for contacting the rich absorber oil with the hot reaction products 25 from said second reaction means in order to partially cool said products, means for fractionating the partially cooled products in order to separate the normally gaseous from the normally liquid constituents, and means for uniting the last mentioned normally gaseous constituents with the 30 fresh gases charged to the system.

10. Apparatus in accordance with claim 9 including means for charging a portion of said rich

absorber oil directly to said fractionating means.

11. Apparatus in accordance with claim 9 including means for collecting heavy condensate in said fractionating means, means for withdrawing said heavy condensate and contacting a portion thereof with hot reaction products from said heating and reaction means, and means for charging another portion of said condensate to said absorption means.

12. The process of converting gas mixtures, 10 containing chiefly C₂, C₃ and C₄ hydrocarbons, to liquid hydrocarbons, which comprises separating the mixture into a fraction containing chiefly C₃ and C₄ hydrocarbons and another fraction containing C₂ hydrocarbons and lighter gases, 15 subjecting each fraction in a separate zone to suitable conditions of time, temperature and pressure for converting the gaseous constituents to liquid hydrocarbons boiling within the gasoline boiling range, separating the bulk of the C₂ and lighter 20 gases from the reaction products of the lighter gases and eliminating them from the system, charging separated normally gaseous and normally liquid reaction products resulting from said conversion of the lighter gases to a common fractionating zone together with the reaction products of the C₃, C₄ hydrocarbons, separating the incondensable gases from the normally liquid hydrocarbons, and uniting the incondensable gases with the fresh gas prior to separation there- 25 of into fractions.

JOHN W. THROCKMORTON.
